UNITED STATES PATENT OFFICE.

EDWARD P. FREDERICK, OF ST. LOUIS, MISSOURI, ASSIGNOR TO THE
BRODERICK & BASCOM ROPE COMPANY, OF SAME PLACE.

DESIGN FOR A PAPER-WEIGHT.

SPECIFICATION forming part of Design No. 24,955, dated December 10, 1895.

Application filed October 26, 1895. Serial No. 567,040. Term of patent 14 years.

To all whom it may concern:

Be it known that I, EDWARD P. FREDERICK, a citizen of the United States, residing in the city of St. Louis, State of Missouri, have invented and produced a new and original Design for a Paper-Weight, of which the following is a specification, reference being had to the accompanying drawing, forming a part thereof.

o The drawing is a perspective view of my improved design for a paper-weight.

The leading feature of my design consists in a rope-like body standing on a base and surmounted by a cap.

5 Referring to the drawing, 1 represents the

body of the paper-weight, which is rope or cable like in appearance, and which preferably is composed of a number of spiral columns 2, each represented by a series of cords or strands, as shown in the drawing. The 20 body is supported on a base 3, and is surmounted by a cap 4 supporting a knob or bulb 5.

I claim as my invention—

The design for a paper weight, substantially 25 as described and shown.

EDWARD P. FREDERICK.

In presence of—

E. S. KNIGHT,

STANLEY STOVER.
